BUCKLE STRAP ASSEMBLING MACHINE

Frank Fertitta, Melrose Park, Ill.

Application February 20, 1946, Serial No. 648,885

13 Claims. (Cl. 223—49)

1

This invention relates to apparatus for assembling a strap into a buckle of the type which is provided with a center bar.

Heretofore, so far as I am aware, buckle straps have been inserted into buckles of the type above mentioned by inserting the ends of the buckle strap manually through the space provided on opposite sides of the center bar. This manual operation is not only tedious but often results in improperly placed straps, particularly where the strap material is relatively short. For example, if it be desired to attach a buckle to a garment, a piece of fabric of the same material from which the garment is made may be formed into a short strap by sewing or folding it and this short strap, just a few inches long, may then be inserted through the buckle, after which the two ends of the strap are sewed together at some suitable place upon the garment. This invention is concerned only with a strap which retains the buckle on the garment and not with a strap which engages with the serrated teeth on the buckle or with any other fastening means that may be provided on the buckle.

While the form of the strap used in connection with this invention is subject to some variation, it is contemplated that a preformed strap of width adapted for insertion through the buckle may be used or a piece of fabric triple that width may be employed. In the event that the triple width is used, the machine will form the fabric into three folds and thereafter insert it through the buckle. In the illustrated embodiment I have shown how the triple width may be employed.

The general object of the invention is to provide means for automatically inserting a buckle strap through a buckle and thereafter discharging the assembled buckle and strap from the machine.

Another object of the invention is to provide means for first folding a piece of fabric in the shape of the buckle strap desired and thereafter inserting it through a center bar buckle strap and discharging the assembled strap and buckle from the machine.

Another object of the invention is to provide a simplified and accurately operating mechanism for folding a piece of fabric into a desired buckle strap, inserting the folded strap through a buckle on opposite sides of the center bar of the buckle so that equal lengths of the strap embrace the center bar.

A further object of the invention is to provide a machine of the character described into which may be placed a buckle having a center bar and

2

a pre-cut piece of flat fabric, and causing the machine first to fold the fabric into a desired arrangement and thereafter to force it through the buckle with equal lengths of the strap on opposite sides of the center bar.

Additional objects and advantages of the invention will be alluded to hereinafter or will become apparent upon a reading of the specification. For the purpose of illustrating the nature of the invention and the manner of using it a preferred embodiment of the invention has been selected for illustration.

Figure 1 is a front elevation showing a machine made in accordance with this invention;

Figure 2 is a side elevation of the same machine;

Figure 3 is a view partly in section and partly in elevation of a portion of the operative parts of the machine showing a buckle positioned in the machine and a piece of fabric ready for the folding operation;

Figure 4 is a view partly in section showing the fabric folded and in the process of being inserted through the buckle;

Figure 5 is a view partly in section showing the buckle strap completely inserted through the buckle, and showing in dotted lines the discharging of the assembled strap and buckle from the machine;

Figure 6 is an enlarged detail view showing a step in the operation of folding the strap;

Figure 7 is another view showing a succeeding step in the operation of folding the strap; and

Figure 8 shows the strap and buckle completely assembled, after their discharge from the machine.

Referring further to the drawing a base 1 is shown having mounted thereon a frame 2 for supporting the vertically movable rods 3 and 4, the latter being connected by means of pin 5 to a foot pedal 6 which may be pivotally mounted upon a bracket 7 on the floor adjacent the machine. While motor driven means or other means for operating the machine may be employed the pedal herein illustrated is adequate to show the operation of the machine.

On the base I provide a plate 8 having a center aperture shaped to receive and position a buckle 9 such as is shown in Figure 8. As these buckles 50 may have various shapes and sizes it will be understood that the aperture indicated as 10 in the plate may be varied in accordance with the buckle being used. Immediately below the aperture I mount a pair of plates 11 and 12, hinged 55 at 13 and 14, for supporting on their opposed

margins the edges 15 and 16 of the buckle, particularly as shown in Figure 5. The downwardly extending serrated edges 17 and 18 of the buckle will clear the edges of the supporting plates, as indicated, and the center bar 19, embraced by the strap in Figure 8 will, of course, lie midway between the opposing edges of the supporting plates.

In order that these plates may yield against a pressure which discharges the buckle I provide each plate with a lateral extension such as 20, to which the coil springs 21 and 22 may be connected, the upper ends of the springs being suitably anchored on the machine on brackets such as 23, to hold the buckle supporting plates snugly against the under side of the apertured plate 8.

Suitably spaced above the base plate 8 I provide a pair of strap supporting plates 24 and 25, each having such a width, as indicated in Figure 7 that the fabric may be wrapped about it in three folded sections to produce the strap shown in Figure 8. These strap supporting members may be mounted as shown in Figure 5 with their ends extending into the cylinders 26 and 27 in which there are provided the posts 28 each of which is surrounded with a coil spring 29 pressing against the bottom of its associated plate, normally holding the two plates horizontally in a common plane, as indicated in Figure 1, yet leaving the plates free to be rocked downwardly against their supporting springs, as each pivots against the shoulder provided on the block 30 carried in the upper part of each cylinder. Obviously the apertures in these plates through which the posts 28 extend must be considerably larger than the diameter of the posts to permit this free downward movement of the strap supporting plates.

As indicated in Figure 3, a piece of fabric is laid upon the two plates 24 and 25. To produce a strap of about the proportions shown in Figure 8, the piece of fabric utilized will be rectangular in shape, its width being substantially three times the width of the plates about which the fabric is wrapped, and its length may be in accordance with the total length desired in the strap.

For wrapping the strap I provide a head 31 which slidably surrounds the shaft 3, so that the shaft may, at the proper time, move relatively to the head. A short spring 32 abutting against the top of the wrapping head and against the boss 33 will constantly urge this head downwardly against an enlarged shoulder 34 provided at the lower end of shaft 3.

Carried on the flanges 35 and 36 of the head are a pair of rock shafts such as 37 each of which has fixed thereon a pair of wrapping plates, those at the rear being numbered 38 and 39. A torsion spring 40 mounted on each shaft 37 in an accustomed manner operates on the shaft to normally hold the wrapping plates in the distended position which they occupy at rest, as shown in Figure 2.

It should be noted, at this point, that the wrapping plates on the two rock shafts may be of slightly different dimensions, or so pivoted that the plates on one shaft may be rotated inside of the pair of plates on the other shaft, which condition is indicated in Figure 7. The two plates on the rear shaft are marked 38 and 39 while the front plates on the front shaft are indicated as 41 and 42.

In order to rotate the wrapping plates during the wrapping operation I extend each shaft such

as 37 beyond the ends of the wrapping head 31, and proportion and shape its ends so that during the downward travel of the wrapping head these extensions will engage the tops of the cylinders 26 and 27. The extensions on one shaft will be shaped differently than those on the other in order to cause one plate to start wrapping before the other does. For example, in Figure 2 it is apparent that the extension 43 connected with the front shaft will strike the cylinder 27 slightly in advance of the extension 44 on the rear shaft, bringing about the consecutive operation of the wrapping plates indicated in Figures 6 and 7.

Accordingly when the operator depresses the foot pedal, shaft 4 will pull down shaft 3 and the spring 32 will cause the wrapping head to follow the shoulder 34 at the lower end of shaft 3. The operating finger 43 will strike the cylinder 27 slightly in advance of the operating finger 44 and cause the two forward plates 41 and 42 to start wrapping the forwardly extending edge of the fabric F in the manner shown in Figure 6, and immediately thereafter the wrapping plate at the rear begins to fold up the rear edge of the fabric. As the operation continues these plates will bring the two folds snugly up underneath the fabric supporting plate.

In order that no cut longitudinal edge of the fabric shall be exposed after the strap is formed I cause one cut edge to be covered because of its position as the middle ply and the other parallel cut edge to lie inside of the fold strap by making the folded plies narrower than the top or outside ply.

After the fabric is wrapped around these resiliently mounted plates 24 and 25 the folded strap should next be delivered to a position closer to the top of the buckle for the insertion operation which next follows. That step in the operation is best shown in Figure 4.

As the wrapping head 31 moves downwardly in response to the action of the pedal 6, the shaft 3 is likewise being lowered and the blades 45 and 46 which are formed integrally thereon will likewise move down, and will strike the folded fabric intermediate the opposing edges of the supporting plates 24 and 25. However, in the meantime, the shoulder corners 47 and 48 on blocks 30 of the wrapping heads will strike the supporting plates 24 and 25 and cause them to bend downwardly as indicated in Figure 4. In the meantime the blades 45 and 46 follow the folded fabric and as the parts approach the position shown in Figure 4 these blades will insert the folded strap through the buckle, on opposite sides of the center bar 19. Inasmuch as the folded fabric is not positively gripped by teeth, prongs or any other such device, it is free to slide off the supporting plates 24 and 25 and does so, being drawn off by the blades 45 and 46 in the manner indicated by dotted lines in Figure 4. The operation then continues until the ends of the fabric are entirely forced through the buckle as shown in full lines in Figure 5.

As the rod 3 reaches the lower end of its full stroke, to attain the position shown in Figure 5 in dotted lines, the part of the rod between the blades 45 and 46 will engage the center bar and push the buckle downwardly, as indicated by dotted lines, in Figure 5, and dislodge it from its support by the buckle supporting plates 11 and 12, which yield downwardly under during this action. The buckle, with the strap retained in it, as shown in Figure 8, may then fall into a delivery chute or receptacle.

The springs 29 which support the fabric supporting plates need not be very strong, and preferably are rather weak, allowing the plates to yield easily at the proper time but restoring them to their horizontal position when the operation is completed.

While the release of the buckle might be accomplished by other means, I find the means employed to be especially satisfactory as the blades 45 and 46 hold the strap snugly about the center bar until the buckle is completely discharged from the machine.

The machine is constructed so that when the fabric is placed either manually or automatically upon the supporting plates 24 and 25, symmetrically over the buckle, it will be folded symmetrically and equal portions of it will be inserted through the buckle. This is advantageous where it is desired to sew the two free ends of the strap simultaneously upon the garment, perhaps into a seam, as is often done in actual practice, when utilizing this invention.

The springs 47 and 48 shown in Figure 2, held under compression between the ends of the cross bar 49 and the bosses 33 and 50 are provided for the purpose of restoring all parts of the machine to normal position after the operator releases the foot pedal. The set screws 51 and 52 may be used for adjustment of the compression of springs 47 and 48.

While I have shown how a piece of cloth may be folded into three sections and thereafter inserted into a buckle, I may also use the machine without the folding apparatus merely for inserting a pre-formed strap into the buckle.

While I have shown and described a preferred embodiment of the invention, it should be understood that the invention is susceptible of considerable variation and modification and that all such variations within the scope of the appended claims are intended to be covered.

Having described my invention I claim:

1. A buckle strap assembling machine comprising means for supporting and retaining a buckle provided with a center bar, said means being movable to free said buckle, a pair of fabric supporting members mounted above the position of the buckle in spaced apart position relatively to each other, means for yieldably supporting said fabric supporting members, means for wrapping said fabric about said fabric supporting members, said wrapping means being mounted both for rotary movement and downward bodily movement while wrapping, means for rotating said wrapping members, means for effecting the downward movement of said wrapping members, means for withdrawing the wrapped fabric from said fabric supporting members and for pushing the fabric through the buckle on opposite sides of said center bar, and means for subsequently releasing the buckle from said buckle supporting means.

2. A buckle strap assembling machine comprising means for positioning and supporting a buckle having a center bar, means for temporarily supporting a sheet of material in a spaced apart position above the position of the buckle, means for folding the sheet into the shape of a strap dimensioned for insertion through the buckle, means for pushing the folded strap through the buckle on opposite sides of said center bar, and means for releasing the buckle thereafter from the machine.

3. A buckle strap assembling machine comprising means for positioning a buckle having a

center cross bar, means for folding a piece of sheet material into the shape of a strap dimensioned for insertion through the buckle, means for applying pressure to the folded strap at both sides of said center bar to force the strap through the buckle until its end portions are free and clear of the buckle, and means for releasing the buckle with the inserted strap therein from the machine.

4. A buckle strap assembling machine comprising means for retaining a buckle provided with a center bar, means for folding a sheet of material into three substantially equal and parallel sections to constitute a strap dimensioned for insertion through the buckle, means for positioning the folded strap adjacent the buckle with substantial portions thereof extending on opposite sides of said center bar, means for forcing said portions of the strap including their ends through the buckle on opposite sides of said center bar, and means for discharging the assembled buckle and strap from the machine.

5. A buckle strap assembling machine comprising means for positioning a center bar buckle, means for folding a piece of sheet material into three overlapping folded sections, and means for inserting the folded sheet through said buckle on opposite sides of said center bar.

6. A buckle strap assembling machine comprising means for retaining a center bar buckle, means for positioning a flat piece of sheet material, means cooperating with said positioning means for folding said piece into three overlapping folded sections, and means for inserting the folded sheet through said buckle on opposite sides of said center bar.

7. A buckle strap assembling machine comprising means for retaining a center bar buckle, spaced-apart supports for a sheet of strap material, means for wrapping said sheet under said support, and means engaging the wrapped sheet in its unsupported area between said supports for thrusting said wrapped sheet through the buckle on opposite sides of said center bar.

8. A buckle strap assembling machine comprising movably mounted spaced-apart supports for a sheet of strap material, means for wrapping opposed marginal portions of said sheet under said supports to form the sheet into three folded sections of substantially equal width, means for retaining a center bar buckle in a position below said supports, and means engaging the folded sheet intermediate its ends for thrusting it downwardly through the buckle on opposite sides of said center bar.

9. A buckle strap assembling machine comprising movably mounted spaced-apart supports for a sheet of strap material, means for wrapping opposed marginal portions of said sheet under said supports to form the sheet into three folded sections of substantially equal width, means for retaining a center bar buckle in a position below said supports, means engaging the folded sheet intermediate its ends for thrusting it downwardly through the buckle on opposite sides of said center bar, and said supports being constructed and arranged to move downwardly toward the buckle during said thrusting action.

10. A buckle strap assembling machine comprising means for retaining a center bar buckle, spaced-apart supports for a sheet of strap material, means engageable with opposite marginal portions of said sheet for wrapping them under said supports to form the sheet into three folded sections of substantially equal width, and a

bifurcated vertically reciprocable member for engaging the folded strap intermediate its ends for removing the strap from said supports and thrusting it through the buckle on opposite sides of said center bar.

11. A buckle strap assembling machine comprising means for retaining a center bar buckle, a pair of spaced-apart supports for positioning a sheet of strap material in a horizontal position above the position of said buckle, means engageable with opposite marginal portions of the sheet material for wrapping said portions under said support to form the sheet into a strap of three folded sections, said wrapping means and supports being constructed to retain the folded sheet during bodily movement of the strap toward the buckle, reciprocating means for moving the strap toward the buckle, and means engaging the strap intermediate its ends for thrusting it through the buckle on opposite sides of its center bar.

12. A buckle strap assembling machine comprising a bed plate provided with an aperture, a pair of pivoted members below said plate for supporting opposite edges of a buckle having a center bar, resilient means normally retaining said members in buckle supporting position, a pair of fabric supporting plates mounted above said bed plate having spaced apart opposed edges and a cylinder associated with each fabric plate, supporting posts in said cylinders and springs associated with said posts operatively connected with said fabric plates to yieldably support them normally in a common horizontal plane, a wrapping head mounted for vertical movement above said fabric plates, said head having pairs of pivoted wrapping members positioned thereon for cooperation with said fabric plates, resilient means normally holding said wrapping members widely spaced apart, means operatively connected with said wrapping members engageable with said cylinders during downward movement of said head for rotating said wrapping members under said fabric plates, a plunger movable initially with said head and later independently movable, means for moving the head and plunger downwardly and means for restoring them to an elevated position, said wrapping members being adapted during downward travel to wrap a piece of fabric about said plates, said plunger being adapted to push the wrapped fabric through the

buckle on opposite sides of said bar and later to discharge the buckle from said buckle supporting members.

13. A buckle strap assembling machine comprising a base, a pair of pivoted members mounted on said base for supporting opposite edges of a buckle provided with a center bar, resilient means normally retaining said members in buckle supporting position, a pair of fabric supporting plates mounted above said plate having spaced apart opposed edges and a cylinder associated with each fabric plate, supporting posts in said cylinders and springs associated with said posts operatively connected with said fabric plates to yieldably support them normally in a common horizontal plane, a wrapping head mounted for vertical movement above said fabric plates, said head having pairs of pivoted wrapping members positioned thereon for cooperation with said fabric plates, resilient means normally holding said wrapping members widely spaced apart, means operatively connected with said wrapping members engageable with said cylinders during downward movement of said head for rotating said wrapping members, a plunger movable initially with said head and later independently movable, means for moving the head and plunger downwardly and means for restoring them to an elevated position, said wrapping members being adapted during downward travel to wrap a piece of fabric about said strap plates, said plunger being constructed and arranged first to push the wrapped fabric through the buckle on opposite sides of said bar and thereafter to apply a downward pressure against said bar to discharge the buckle from said buckle supporting members by rotating them downwardly.
